United States Patent Office

Des. 218,040
Patented July 14, 1970

218,040

ELECTRICAL CONNECTOR

James W. M. Bee, Toronto, Ontario, Canada, assignor to
Marr Electric Limited, Cooksville, Ontario, Canada

Filed June 4, 1969, Ser. No. 17,520

Term of patent 14 years

Int. Cl. D13—99

U.S. Cl. D26—1

FIG. 1

FIG. 3

FIG. 2

FIG. 4

FIG. 1 is a perspective view of the electrical connector according to this invention;

FIG. 2 is an end view looking directly at the longer of the major axes of the electrical connector;

FIG. 3 is a top view looking directly down on the electrical connector; and

FIG. 4 is an end view looking at the shorter of the minor axes of the electrical connector.

I claim:

The ornamental design of an electrical connector, as shown and described.
